(57) **CLAIM**

The ornamental design for a adapter for a screwdriver head, as shown and described.

DESCRIPTION

FIG. 1 is a front perspective view of a adapter for a screwdriver head, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged plan view of its top surface; and,

FIG. 8 is an enlarged plan view of its bottom surface.

The broken lines in the drawings illustrate the portions of the adapter for a screwdriver head, which form no part of the claimed design.

1 Claim, 8 Drawing Sheets
